Des. 239,701
Patented Apr. 27, 1976

239,701

CAR WASH BUILDING

James W. Baker, Santa Monica, Calif., assignor to Daniel C. Hanna, Portland, Oreg.

Filed Oct. 15, 1973, Ser. No. 406,628

Term of patent 14 years

Int. Cl. D25—03

U.S. Cl. D25—25

FIG. 1

FIG. 2

FIG. 3

FIG. 1 is a perspective view of a car wash building embodying my new design;

FIG. 2 is a side elevation view of the car wash building; and

FIG. 3 is a front elevation view of the car wash building.

I claim:

The ornamental design for a car wash building, as shown.
